UNITED STATES PATENT OFFICE.

CHARLES W. UNKLE AND THEODORE D. GRILEY, OF BALTIMORE, OHIO.

TUB-BEATER.

1,244,144.

Specification of Letters Patent. Patented Oct. 23, 1917.

Application filed June 15, 1917. Serial No. 174,843.

To all whom it may concern:

Be it known that we, CHARLES W. UNKLE and THEODORE D. GRILEY, citizens of the United States, residing at Baltimore, in the county of Fairfield and State of Ohio, have invented a certain new and useful Improvement in Tub-Beaters, of which the following is a specification.

This invention relates more particularly to machines for the reduction of paper to pulp and are commonly known in practice as tub beaters. In the use of the machine of this kind now commonly employed there is a large waste of time and energy due to the action of the machine upon material that is sufficiently reduced before the entire mass is reduced. It is the object of the present invention to avoid at least some measure of this waste by a construction adapted to remove from the tub all or a portion of the sufficiently reduced material prior to the reduction of the whole mass.

The invention resides in the means embodied in the example shown in the accompanying drawing and set forth in the following description, the features of novelty being finally claimed.

In said drawing—

Figure 1 is a top plan view with portions in section.

Fig. 2 is a partial section on the line II—II Fig. 1, looking to the left.

In the views 5 designates the elongated tub in which the paper to be pulped with the necessary water or other liquids used in the process are placed. Secured in this tub longitudinally is the usual midfeather 6 of such length and so placed as to permit a circulation of the material around the tub when it is impelled at one side of the midfeather.

In one of the spaces between the midfeather and a side of the tub is the usual roll 7 of wood and containing knives or fly-bars coöperating with the usual bed plate 45 (not shown) in the bottom below. The roll is fastened to a shaft 8 provided with a belt pulley as at 9 for driving the roll. The tub also contains the usual back fall at 10.

The roll is inclosed at its upper side in a hood 11 and in a flattened portion at 12 of that side of the hood opposite the back fall we provide a series of perforations 13. Secured on a rod 14 lying on the flat portion 12 is a series of plates 15 having sharp edges 55 so that when the rod is reciprocated the plates cut portions of the paper stock pro-

truding through all the perforations and clear them for the passage of material as hereinafter further explained.

To reciprocate the rod we provide the following means:

That end of the shaft containing the roll is provided with a spur gear 16 to mesh with a spur gear 17 journaled in a suitable bracket 18. The spur gear 17 has connected with it a beveled gear 19 which in turn meshes with a beveled gear 20 on one end of a short shaft 21 journaled in a suitable bracket 22 on the side of the tub. The other end of the shaft 21 is provided with a disk 23 having a crank pin 24 that works in a slotted yoke 25 secured to the end of the aforesaid rod 14. When the shaft 8 is rotated, therefore, the revolution of the crank pin 24 imparts a rectilinear reciprocating motion to the rod 14.

Located below the perforation 13 is an inclined trough or gutter 26 which is extended beyond the opposite side of the tub so as to discharge the pulp into a suitable receptacle placed there for the purpose.

The gutter 26 has a lateral discharge 27 into the tub beyond the midfeather.

28 designates a removable gate fitting in grooves 29 of the lateral discharge 27 so that the contents of the gutter will be directed to the receptacle beyond the tub. When said receptacle is to be removed or changed the gate 28 is placed in the grooves 30 thereby causing the contents of the gutter to discharge into the tub. The flow of the contents of the gutter can thus be changed without stopping the pulping operation.

In practice the roll is turned in the direction of the arrow Fig. 2 and centrifugal action throws the stock against the inner side of the flat portion 12. The perforations permit the sufficiently reduced portions to pass through said perforations and into the gutter. The larger portions clog and protrude through said perforations but are cut off, removed or pushed back into the tub by the reciprocated plates 15.

The forms of the parts can be changed without departing from the gist of the invention as claimed.

What we claim is:

1. In a paper pulping machine, the combination, with a tub and beater therein, of a hood for the beater, a perforated member against which the pulp is thrown by centrifugal action to separate the sufficiently re-

duced portions from the insufficiently reduced portions thereof, clearing means acting on said perforated member for preventing the clogging thereof by the insufficiently reduced portions, and means for conducting away the material discharged through said perforations.

2. In a paper pulping machine, the combination, with a tub and beater therein, of a 10. hood for the beater provided with a perforated portion against which the pulp is thrown by centrifugal action, means for preventing the clogging of said perforations consisting of a device reciprocated across 15 said perforations, and means for carrying away the material discharged through said perforations.

3. In a paper pulping machine, the combination, with a tub and beater therein, of a 20. hood for the beater provided with a perforated portion against which the pulp is thrown by centrifugal action, means for preventing the clogging of said perforations

and means for conducting away the material discharged through said perforations 25 consisting of a conductor having a lateral discharge into the tub and a discharge to the exterior of the machine and means whereby either of said discharges may be closed independently of the other.

4. In a paper pulping machine, the combination, with a tub and beater therein, of a hood for the beater, and means for separating the sufficiently reduced portions of pulp from insufficiently reduced portions thereof 30 consisting of a perforated member against the inner side of which the pulp is thrown by centrifugal action, means for preventing the clogging of said perforated member consisting of a clearing device and 35 means for moving the same across the outer side of said perforated member, and means for carrying away the material discharged through said perforated member.

CHARLES W. UNKLE.
THEODORE D. GRILEY.
